UNITED STATES PATENT OFFICE.

JOHN RUSSELL, OF BERLIN, PENNSYLVANIA.

GRAIN-SEPARATOR.

SPECIFICATION forming part of Letters Patent No. 284,490, dated September 4, 1883.

Application filed February 23, 1883. (No model.)

To all whom it may concern:

Be it known that I, JOHN RUSSELL, a citizen of the United States, residing at Berlin, in the county of Somerset and State of Pennsylvania, have invented certain new and useful Improvements in Grain-Separators; and I do declare the following to be a full, clear, and exact description of the invention, such as will enable others skilled in the art to which it applies to make and use the same, reference being had to the accompanying drawings, and to letters and figures of reference marked thereon, which form a part of this specification.

This invention relates to that class of grain-separating machines in which the grain is cleaned by the action of induced air-currents. The invention consists of a double grain-separator in which the parts are constructed and arranged as hereinafter described and claimed, whereby the capacity of the machine is largely increased without involving a proportionate increase in bulk.

In the annexed drawings, Figure 1 represents a longitudinal sectional elevation of my improved grain-separator on the line $y y$ of Fig. 2. Fig. 2 is a transverse vertical section on the line $x x$ of Fig. 1. Fig. 3 is an end view, partly in section. Fig. 4 is a transverse section on the line $z z$ of Fig. 1.

30 A represents the frame-work of the machine. B is a vertical shaft journaled in a step in the bridge-tree A'. The shaft B has a pulley near its lower end, by means of which it is driven by a belt or chain from any suitable 35 motor. To this shaft is secured a fan, B', that revolves in the fan-case B², which is provided with the opening or mouth a , as seen in Fig. 1.

C is the air-chamber, communicating with 40 the fan-case by means of an opening, b , around the shaft. Above the air-chamber C, and journaled in suitable bearings, is a vertical shaft, c, provided with a pulley and an eccentric, c', to which is secured a pitman, D, the 45 other end of which pitman is fastened to the under side of the inclined shoe E. A belt passing from a pulley on the upper end of the shaft B to the pulley on the shaft c rotates the shaft c and operates the pitman, thus vibrating the shoe E. This vibratory shoe is supported by the springs d d', and is provided with a hopper and two screens, as shown in

Fig. 1. It also has a longitudinal partition, e², as shown in Fig. 2, for the purpose of effecting a more equal division of the quantity 55 of grain delivered therefrom to the opposite sides of the inclined spout H.

The grain is first fed into the machine through the hopper F, from which it passes down the double-inclined plane F', through the ports e e, 60 into the conductors or spouts G G on both sides of the machine, where it is subjected to upward currents of air induced toward the air-chamber by the revolutions of the fan B'. These drafts of air carry the dust, chaff, and 65 lighter particles up over the arches e' e' and down into the suction-spouts G' G', whence the chaff passes through the openings f f into the air-chamber C, and through the aperture b of the same to the fan, and is allowed to escape 70 through the mouth a. The screenings and heavier particles pass out at the inclined bottoms through the valves f' f', as indicated in Fig. 2. The drafts in the spouts G' G' are regulated by means of the adjustable deflectors 75 or valves g g, to prevent the valuable portions of the cleanings from entering the air-chamber. The grain thus freed from dust and chaff next passes from the spouts G G to the inclined shoe E, the upper screen carrying off the straw, 80 corn-cobs, and larger foreign substances by a spout or other means (not shown) to the side of the machine, while the grain falls through the upper to the lower screen, the sand and other smaller impurities passing through the lower 85 screen, and being conveyed from the end of the same by a spout (not shown) to the side of the machine. The grain thus cleaned passes from the shoe to the double-inclined spout H, which 90 extends across the machine to the arched suction-spouts II on each side. The grain passes through the ports h h into the spouts I I, as seen in Fig. 3, and is a second time freed from dust, &c., by an upward current of air induced toward the air-chamber by the revolutions of the fan. The dust and chaff are carried 95 by the current through the spouts I I, through openings k k, into the air-chamber, as seen in Fig. 4, and by the opening b to the fan, and then allowed to waste into the open air at a, or be received in suitable receptacles, after which the grain passes out of the spouts I I by means of the spouts i i (see Figs. 3 and 4) into hoppers i' i', which convey it to the suction-tubes J J,

through which it escapes, and where it is subjected to a third and final upward draft of air created by the fan B', which carries up any remaining light impurities over the arches into 5 the spouts J' J' and into the air-chamber through the ports k' k', (see Fig. 4,) the screenings passing out through the valves l' l' at the ends of the inclined bottoms, as seen in Figs. 1 and 3. The drafts in the spouts J' J' are 10 regulated by means of the adjustable valves or deflectors l l, having set-screws l''. The grain thus cleaned passes out at the open ends of the spouts J J.

It will thus be seen that the grain while passing 15 through the machine is subjected to the cleaning action of strong air-currents at three distinct points on each side of the double machine—at first just before reaching the vibratory shoe, again immediately after passing the 20 shoe, and finally after leaving the hoppers i' i' before escaping from the machine. These air-currents are all induced by the fan B', which draws the dust and chaff into the air-chamber, whence it is discharged through the opening 25 a, the air-currents thus induced being sufficiently powerful to effect a thorough cleansing of the grain.

By arranging the vibratory shoe E to act in conjunction with a double incline, F', and a 30 spout, H, diverging to each side of the machine, and arranging the suction-spouts in the manner described, so as to receive and discharge grain on both sides of the machine against the action of induced air-currents passing through said suction-spouts to the fan-case, 35

I am enabled to largely increase the capacity of such machines without a proportionate increase in bulk or space. This machine is capable of effecting a thorough separation of all extraneous substances of less weight than that 40 of the grain under treatment.

Having thus described my invention, what I claim as new, and desire to secure by Letters Patent, is—

1. In a grain-separator, the combination, 45 with the vibratory shoe E and a single fan, B', of the hopper F, double-inclined plane F', double-inclined spout H, arched suction-spouts I I, and the arched suction and discharge spouts G' G' and J J', said suction-spouts communicating with the fan-case through suitable openings, whereby the grain is cleaned and discharged in divided streams or portions, substantially as described. 50

2. In a grain-separator, the combination, 55 with the vibratory shoe E, having a central partition and carrying suitable screens, of the double-inclined plane F' and double-inclined spout H, substantially as described.

3. In a grain-separator, the combination of 60 the vibratory shoe E, double-inclined spout H, arched suction-spouts G' G', I I, and J J', spouts i i, and hoppers i' i', substantially as described.

In testimony whereof I affix my signature in presence of two witnesses.

JOHN RUSSELL.
